HEATING METHOD AND APPARATUS

Dion K. Dean, Rahway, N. J., assignor to Foster Wheeler Corporation, New York, N. Y., a corporation of New York

Application July 2, 1938, Serial No. 217,133

9 Claims. (Cl. 237—1)

My invention relates to high temperature heating systems of the type in which vapor of a high boiling point liquid such as diphenol, diphenol oxide, "Dowtherm," or other suitable substance, 5 is used as a heating medium in industrial processes, such as the deodorization of animal or vegetable oils and the like. In such systems, the vapor is ordinarily generated in a boiler or similar heating device and then conducted directly 10 to a point of use where it is brought in heat exchange relationship with the material to be heated, the condensed vapor thereafter being returned to the boiler for reheating. Although this practice is satisfactory when the required vapor 15 temperatures are such that none of the material is heated above the chemical breakdown point, it is not satisfactory when the required vapor temperatures are at such level that some portion of the material is heated above the chemical 20 breakdown point. This is so for the reason that in vapor generating apparatus, such as boilers or the like, some of the fluid being heated, particularly the fluid which is directly in contact with the heating surface, will be elevated to a temperature 25 higher than that of the vapors generated in the apparatus, the degree of such higher temperature over that of the vapors generated depending ordinarily upon the particular generating apparatus used. Accordingly, it is quite 30 possible that in delivering vapors of a given temperature from fluid heating apparatus, some parts of the fluid may be heated to a temperature so high that chemical decomposition may take place.

35 It is the object of my invention to provide a method of, and means for, heating with vapors by employing vapors which have been raised in temperature beyond a point at which chemical decomposition would take place in fluid heating apparatus by such means that the chemical composition of the heating material is not injuriously affected, whereby the temperature range of the vapors as heat transfer agents is materially extended. This is accomplished, generally 40 stated, by applying a relatively small amount of heat in the form of mechanical energy to the vapors which will make available a large amount of latent heat at a temperature level above the temperature at which it can safely be delivered 45 by fluid heating equipment without subjecting the heating material, or any portion thereof, to the deleterious effects of overheating.

For a better understanding of the particular features that characterise my invention, reference 50 may be had to the following description

considered in connection with the accompanying drawing in which the single figure is a generally diagrammatic view of a high temperature heating system embodying my invention.

Referring to the drawing, reference character 5 10 designates a boiler or vapor generator to which an initial charge or "make up" of the desired liquid or material may be supplied by any suitable means, not shown, and wherein the vapor will ordinarily be generated at the maximum 10 temperature possible short of the chemical breakdown point of any portion of the liquid, although it may be heated to temperatures lower than said maximum temperature, if desired. The vapors produced in the boiler are conducted 15 through a line 11 to a compressor 12 which may be a direct acting or centrifugal compressor, by means of which the vapor is compressed, and the pressure and corresponding temperature thereof is increased to the desired level without 20 overheating and consequent chemical breakdown of any portion of the material in the circuit. From the compressor, vapor line 13 conducts the high temperature vapor to a point of use, which as shown consists of a coil 14 through which 25 the vapor from line 13 flows, and which is submerged in a shell or tank 15 containing the material to be heated by indirect contact with said vapor. A trap 16 provided with a float valve 17 receives the cooled or condensed vapors from 30 the coil 14. When the body of condensate in trap 16 reaches a sufficient height, the float valve 17 will open and discharge the condensate through line 18 to a flash chamber 19 which has 35 its upper portion connected by line 20 to the inlet or suction side of the compressor. A condensate return line 21 connects the bottom of the flash chamber 19 with the boiler 10. Since the pressure on the condensate within the flash chamber will be approximately that of the boiler, 40 vapors will be flashed off therein and will be returned to the suction side of the compressor, while the remaining condensate in the flash chamber will be returned to the boiler through line 21, thus completing the cycle. 45

In the event superheating takes place during compression of the vapors, this may be prevented by mixing some of the condensate of the vapor with the vapor to be compressed. One means for accomplishing this purpose comprises 50 a line 22 between the trap 16 and the suction of the compressor, (connecting with line 11) and by means of a valve 23 in line 22, a governed quantity of condensate may be returned through this line to the suction of the compressor. The 55

condensate would enter the compressor preferably in the form of mist and thus prevent over-heating of the vapor during the compression step.

5 It will thus be perceived that by employing the present invention, vapors may be utilized for heating purposes which are higher in temperature than vapors which can ordinarily be obtained from vapor generating equipment without 10 out chemical breakdown of the material or any portion thereof. The invention is capable of general application and is not limited in its use to the specific materials mentioned herein.

By the expression "chemical breakdown point" 15 as used herein and the expression "critical temperature" as used in the claims, is meant that temperature of the vapors of the material being used as the heating medium, which if generated by the application of heat in a boiler or similar 20 apparatus, and elevated to said temperature, would entail the heating of at least some of the fluid to the temperature of chemical decomposition.

Although I have illustrated and described a 25 preferred form of apparatus for carrying out my invention, it is to be understood that changes may be made in the specific form and arrangement of parts disclosed and in the method and the several steps thereof without departing from 30 the principles of the invention which is not to be limited excepting by the scope of the appended claims.

What I claim is:

1. The method of heating substances by heat 35 exchange with vapor of a material subject to chemical decomposition when heated by combustion gases beyond a critical temperature which comprises producing vapor of the material by means of combustion gases at temperature levels below said critical temperature, increasing the temperature of the vapor to the desired point above said critical temperature without chemical decomposition of any portion 40 of the material, by compressing the vapor, and bringing the compressed vapor into heat exchange relationship with the substance to be heated.

2. The method of heating substances by heat 50 exchange with vapor of a material subject to chemical decomposition when heated by combustion gases beyond a critical temperature which comprises producing vapor of the material by means of combustion gases at the maximum temperature below said critical temperature, increasing the temperature of the vapor to the desired point above said critical temperature without chemical decomposition of any portion 55 of the material, by compressing the vapor, and bringing the compressed vapor into heat exchange relationship with the substance to be heated.

3. The method of heating substances by heat 60 exchange with vapor of a material subject to chemical decomposition when heated by combustion gases beyond a critical temperature which comprises producing vapor of the material by means of combustion gases at temperature levels below said critical temperature, increasing the temperature of the vapor to the desired point above said critical temperature without chemical decomposition of any portion 65 of the material, by compressing the vapor, bringing the compressed vapor into heat exchange relationship with the substance to be heated in a heating zone wherein part at least of

the vapor is condensed, and mixing condensate of the vapor with vapor to be compressed prior to compression to thereby prevent superheating of the vapor upon compression.

4. The method of heating substances by heat 5 exchange with vapor of a material subject to chemical decomposition when heated by combustion gases beyond a critical temperature which comprises producing vapor of the material by means of combustion gases at temperature levels below said critical temperature, increasing the temperature of the vapor to the desired point above said critical temperature without chemical decomposition of any portion of the material, by compressing the vapor, 10 bringing the compressed vapor into heat exchange relationship with the substance to be heated in a heating zone wherein part at least of the vapor is condensed, conducting condensate to a flash zone, conducting vapor evolved in 15 the flash zone to the zone wherein said vapor is compressed, and returning the remaining condensate to the vapor producing zone.

5. The method of heating substances by heat 25 exchange with vapor of a material subject to chemical decomposition when heated by combustion gases beyond a critical temperature which comprises producing vapor of the material by means of combustion gases at temperature levels below said critical temperature, increasing the temperature of the vapor to the desired point above said critical temperature without chemical decomposition of any portion 30 of the material, by compressing the vapor, bringing the compressed vapor into heat exchange relationship with the substance to be heated in a heating zone wherein part at least of the vapor is condensed, 35 mixing condensate of the vapor with vapor to be compressed prior to compression to thereby prevent superheating of the vapor upon compression, conducting condensate to a flash zone, conducting vapor evolved in the flash zone to the zone wherein said vapor is compressed, and returning the remaining condensate to the vapor producing 40 zone.

6. Apparatus for heating substances by heat 45 exchange with vapor of a material subject to chemical decomposition when heated by combustion gases beyond a critical temperature, comprising means for producing vapor of the material by combustion gases at a temperature level below said critical temperature, compressor means for increasing the temperature of the vapor to the desired point above said critical temperature without chemical decomposition of any portion 50 of the material, means for bringing the compressed vapor into heat exchange relationship with the substance to be heated, during which part at least of the vapor is condensed, 55 means for conducting condensate to a flash chamber, means for conducting vapor from the flash chamber to said compressor means, and means for conducting condensate from the flash chamber to the vapor producing means.

7. Apparatus for heating substances by heat 60 exchange with vapor of a material subject to chemical decomposition when heated by combustion gases beyond a critical temperature, comprising means for producing vapor of the material by combustion gases at a temperature level below said critical temperature, compressor means for increasing the temperature of the vapor to the desired point above said critical temperature without chemical decomposition of any 65

portion of the material, means for bringing the compressed vapor into heat exchange relationship with the substance to be heated, during which part at least of the vapor is condensed, 5 means for mixing condensate of the vapor with vapor to be compressed to prevent superheating of the vapor upon compression, means for conducting condensate to a flash chamber, means for conducting vapor from the flash chamber to 10 said compressor means, and means for conducting condensate from the flash chamber to the vapor producing means.

8. The method of heating substances by heat exchange with vapor of a material subject to 15 chemical decomposition when heated beyond a critical temperature which comprises producing vapor of the material at temperature levels below said critical temperature, increasing the temperature of the vapor to the desired point 20 above said critical temperature without chemical decomposition of any portion of the material, by compressing the vapor, and bringing the

compressed vapor into heat exchange relationship with the substance to be heated.

9. Apparatus for heating substances by heat exchange with vapor of a material subject to chemical decomposition when heated beyond a critical temperature, comprising means for producing vapor of the material at a temperature level below said critical temperature, compressor means for increasing the temperature of the vapor to the desired point above said critical 10 temperature without chemical decomposition of any portion of the material, means for bringing the compressed vapor into heat exchange relationship with the substance to be heated, during which part at least of the vapor is condensed, 15 means for conducting condensate to a flash chamber, means for conducting vapor from the flash chamber to said compressor means, and means for conducting condensate from the flash chamber to the vapor producing means. 20
